UNITED STATES PATENT OFFICE

2,636,538

TWISTING MACHINE FOR SILL STEPS

George E. Algatt, Berwick, Pa., assignor to American Car and Foundry Company, New York, N. Y., a corporation of New Jersey

Application December 9, 1949, Serial No. 132,154

1 Claim. (Cl. 153—78)

1

This invention relates to twisting means for bar stock and in particular to twisting means for placing a right angle twist in bars intended for sill steps on freight cars.

In the past sill steps have been made by shaping the hot sill step then after cooling and reheating the ends were individually twisted to produce the desired form. Such an operation was extremely expensive since it required a plurality of heats and a plurality of operators. It is an object, therefore, of the present invention to provide a twisting machine for bar stock which can positively control the exact point and type of twist and which will require but a single operator.

A further object of the invention is the provision of a bar twisting machine permitting exact control of the length of twist and the axis about which the twist occurs.

A still further object of the invention is the provision of twister die blocks for holding bar stock, which blocks permit at least four types of twists to be made per set of blocks.

These and other objects of the invention will be apparent to persons skilled in the art from a study of the following description and accompanying drawings, in which

Fig. 1 is an elevational view of the improved machine;

Fig. 2 is a sectional view taken substantially on line 2—2 of Fig. 1;

Fig. 3 is a sectional view taken substantially on line 3—3 of Fig. 1;

Fig. 4 is a sectional view similar to Fig. 2 but showing the die blocks in a different position, and

Fig. 5 is an elevational view of a completed sill step.

Referring now to the drawings in detail it will be seen that the machine is mounted on a table or other supporting structure 2 and is preferably made in duplicate halves, each having a base 4 to which is bolted or otherwise secured angle shaped guides 6 which, together with the base, form slideways for clamp members 8 and die holders 10. The clamp members 8 are formed of solid blocks having the top portion notched to receive a bar retainer 12 clamped in position by set screws 14. Handled clamp screws 16 extend through the block and through the bar retainer so as to firmly grip the bar B, as clearly shown in Fig. 3. To the bottom of each block is fastened a plate 18 threaded to receive an adjusting clamp screw 20 by means of which the clamp member may be longitudinally adjusted in the

2

slideways and firmly clamped in the desired position.

Each of the die holders 10 is formed of a block adapted to slide within a slideways under control of an air or other fluid cylinder C to which it is connected by piston rod 22. Air or other motive fluid will be supplied to the cylinders through pipes 24. On the side opposite piston 22 the die holder is equipped with adjustable stop members 26 which are adapted to contact the clamp members 8 thereby providing a definite predetermined spacing between the die holder and the clamp members. The die holders are slotted as at 30 to permit an operating handle 32 to be moved therein and the handle is fastened to a circular die retaining block 34. This circular die retaining block is provided with a rectangular opening 36 in which may be slid a pair of dies 38. Each die half is provided with a half of a rectangular opening which, when the halves cooperate, will provide a rectangular opening for the reception of the bar B. As shown in Fig. 2 the halves 38 are assembled so that the axis of rotation is substantially centrally located with respect to the bar to be twisted. In Fig. 4, however, the blocks 38 are turned over end for end as a unit to reposition the rectangular opening in the die block so that the axis of rotation is adjacent the lower edge of the bar B. If it be desired to obtain other types of twists the blocks 38 of Fig. 2 and Fig. 4 may be separated and the outer slots 50 brought into adjacent relationship so as to provide bar receiving slots with the axis of twists located differently than in Figs. 2 and 4, thus it will be seen that by means of a single pair of dies four types of twists may be quickly obtained by merely shifting the position of the dies in the openings of the circular die holder. As clearly shown, the dies are held in place by means of straps 52 bolted or otherwise secured to the rotary die holder.

In operation the straight and heated bar B will be dropped into the clamp members 8 and clamped by means of handled set screws 16, after which air or other motive fluid will be applied to cylinders C moving them longitudinally toward each other and over the ends of the bar B. The fluid pressure in the cylinders C will firmly hold stops 26 against the clamp members at a predetermined distance previously set. With the parts in this closed position the handles 32 may be pulled downwardly in the desired direction to a position such as shown in the line and dash of Figs. 2 and 4. It will be noted that with the dies in the position shown in Fig. 2 rotation

will place the center twist substantially on the longitudinal axis of the bar, whereas if the dies are in the position shown in Fig. 4 the rotation will be about an axis adjacent the lower edge of the bar. It will also be obvious that if the dies are separated and turned end for end toward each other the slot halves will register and rotation would then place a twist in the bar with the center slightly below the lower edge of the bar. In cases where the dies are rotated end for end toward each other from the position of Fig. 4, then the twist would take place about a center positioned slightly above the longitudinal center of the bar. After the desired twist of the bar has been accomplished the cylinders will be actuated to pull the die holders off the end of the twisted bar and the handles can then be returned to their upright or full line position in readiness to repeat the operation on a subsequent bar. Following the twisting of the bar ends it may be immediately removed from the machine by loosening clamps 16 and the final bends made to produce the finished sill step as shown in Fig. 5 and without any reheating of the bar.

While the invention has been described more or less in detail with particular reference to the accompanying drawings it will be obvious that various modifications and rearrangements of parts may be made without departing from the scope of the invention as defined by the following claim.

What is claimed is:

In a bar twisting machine, the combination of a base formed with a slideway, a clamp member adjustably carried by the slideway, said clamp member including a block formed with a vertical recess in its upper wall, a bar retainer comprising a body formed with a vertical slot extending through its upper face, said bar retainer being adapted to seat in the recess in said block, means for clamping said bar retainer in the recess in said block, means extending through the block

and the bar retainer for clamping stock material in the slot in said bar retainer, a die holder slideable in the slideway in said base, said die holder including a block formed with a central bore, an adjustable stop projecting from the inner face of the die holder for abutment with the clamp block to limit the spacing between the clamp block and die holder, a die retaining block positioned in said bore for rotary movement, said die retaining block being formed with an axially aligned rectangular opening, a pair of dies arranged in said rectangular opening, said dies normally filling said rectangular opening and having their abutting faces formed with cooperating slots which register to provide an opening of the same diameter as the slot in said bar retainer, said slots being formed off center from the transverse medial plane of said dies whereby reversal of said dies will shift said rectangular opening from its previous plane, handle means for rotating said die retaining bar, and power means for moving the die holder along its guideway.

GEORGE E. ALGATT.
